SNOWPLOW

Gerrit Wandscheer, Sioux Center, Iowa

Application September 25, 1939, Serial No. 296,460

5 Claims. (Cl. 37—43)

My invention relates to a snow plow for highway use.

An object of my invention is to provide a snow plow which includes a conveying member which bores spirally in the road bed in the direction of travel and thereby positively drags the snow rearwardly into the mechanism for conveying the snow thus impelled to the sides of the roadway.

A further object of my invention is to provide auxiliary end boring members which assist in conveying the snow into the fan.

A further object of my invention is to provide the auxiliary members so arranged to provide the most positive action.

A further object of my invention is to tilt the entire plow arrangement so that the effective edges will be more favorably disposed for the cutting operation.

A further object of my invention is to provide a spout arrangement which can be readily forced to either side of the plow for deflecting snow to either side of the roadway.

A further object of my invention is to provide a fan structure which can be reversed independently of the other units, and to provide a structure which breaks down the side walls of the snow as the machine progresses, and to provide such a structure which can be built at a reasonable cost of manufacture.

With these and other objects in view, my invention consists in the construction, arrangement and combination of the various parts of my device, whereby the objects contemplated are attained, as hereinafter more fully set forth, pointed out in my claims, and illustrated in the accompanying drawings, in which:

Figure 1 is a transverse section taken longitudinally along the axis of the plow,

Figure 2 is a sectional view taken along the lines 2—2 of Figure 1,

Figure 3 is a forward elevation,

Figure 4 is a rear elevation,

Figure 5 is a modified form of the fan reversing arrangement, and

Figure 6 is a sectional view taken along the lines 6—6 of Figure 5.

I have used the character 10 to designate generally a truck or other such means for pushing the plow forwardly. Attached to the vehicle 10 are the braces 11 and 12 which are attached to the vertical channeled members 13. Received within the members 13 are the slideable members 14 (see Figure 4) which are attached to a cross bar 15. The bar 15 is attached at 16 to the plunger 17 which is attached to a piston in the

cylinder 18. A hydraulic line 19 runs to the vehicle and pressure applied within the cylinder 18 will raise the plow to a desired elevation. The cylinder 18 is mounted upon the bracket 20 which is attached to the stationary portions 13. A cylindrical drum 21 which includes the rear wall 22 and a forward wall 23 carries the fan blades 24.

The forward wall member 23 includes the cut out portions at 25 (see Figure 3) and the lower end of the wall 23 includes a bearing 26 into which is journaled the shaft 27. The shaft 27 extends forwardly and is attached to the hub 28 which hub is attached to the deflecting spokes 29 which spokes in turn are attached to the cutting blades 30. The blades 30 are bent in an outward spiral but are of limited length and each of such blades is upon its own line of curvature with the rear ends 31 being slightly inwardly from the outer ends 32. The blades are attached to the spokes 29 at 33. The shaft 27 extends rearwardly and is journaled within the bearing 34. Affixed to the shaft 27 is the large gear 35. A further hollow shaft 36 is journaled within the bearing 37 and to a casing 38 at 39. Attached to the hollow shaft 36 is a sprocket 40 over which passes the chain 41 which in turn engages a further sprocket 42 which sprocket 42 is freely journaled upon the shaft 43 which is journaled at 44. The shaft 43 extends into the square shaft portion 45 upon which is mounted a gear 46 which is locked against rotation upon the square portion 45 but which, however, can be moved longitudinally along the shaft 45. The gear 46 is adapted to mesh with the further gear 47 during a certain rotational direction of the fan and the gear 47 is affixed to the shaft 36. A further smaller gear 48 is attached to the forward extremity of the shaft 43. A small fork member 49 passes through the casing at 50 to the connection at 51 which is controlled by means of the member 52 from the vehicle. The casing 38 is supported by means of a suitable annular ring 53 and it will be noted that practically all of the casing is within the fan structure with the exception of certain minor projecting portions. The shaft 43 extends to the universal connection 54 which is connected at 55 to the vehicle. A pair of forward shafts 56 and 76 are attached to the hubs 57 which merge with the spokes 58 which spokes are attached at 59 to the blades 60. The blades 60 are alike in practically all respects to the blades 30 except that the blades 60 are smaller and they are arranged in substantially the same manner and the structure formed be-

tween the spokes 58 and the blades 60 form a similar unit to the larger members with the exception that they are considerably smaller.

It will be noted that there are two of such units situated at the rear lower corner of the plow casing. The side cutting members 61 converge toward the rear of the plow and merge with the wall 23 and an arcuate shield 62 merges with the horizontal member 63 which in turn are attached to the side members 61. A lower cutting arrangement is provided by means of the plates 64 which extend into the cutting edges 65 which extend rearwardly and upwardly forming a V shaped structure.

The blades 60 rotate in the direction shown by the arrows 66 which in effect is in opposed relation and each series of blades thereby operates toward the center of the machine. The fan blades 24 are connected at 67 to the spokes 68 which in turn are connected to the hub 69 which is attached to the hollow shaft 36. The shaft 56 which is attached to the forward blades 60 extends rearwardly through the casing and is attached to the sprocket 70 over which passes the chain 71. The chain 71 engages a further sprocket 72 and the arrangement is enclosed by means of the casing 73. The shaft 27 also extends rearwardly through the bushing 34 and is attached to a further sprocket 74 over which passes the chain 75 and which chain passes over a suitable sprocket to drive the further shaft 76 which is connected to the other series of blades 60 attached to the other rotating member as shown in Figure 3. Since the shaft 27 is driven through engagement with the gear 48 the shafts 27 and 43 are rotated in an opposed direction.

Since the sprockets 70 and 74 are connected to such shafts, their direction of rotation will be correspondingly opposite and the blades 60 are thereby rotated as explained in the direction of the arrows 66. It will be noted that the sprocket 72 will be larger than the sprocket in the casing 71 which encloses the upper shaft arrangement, and this is necessary to correspondingly decrease the speed so that the blades 60 will travel at the same speed. During normal operation of the plow it is necessary to change the direction of rotation of the fan blades 24.

As shown in Figure 1 the rotation of the blades will be in one direction due to the attachment to the hollow shaft 36. This is caused by the locking of the gear 46 with the gear 47 and meanwhile the gear 42 is riding freely upon the shaft 43. To change the direction of the fan, however, the fork member 49 is pushed inwardly by means of the members 52 which carry the gear 46 into locked engagement with the shoulder 78 which includes suitable locking indents, so that as a result the sprocket 42 will be effectively locked against rotation and will rotate the further sprocket 40 through the chain 41. Since the arrangement is then not a reverse gear arrangement but is directly chain driven, correspondingly the direction of the fan will be reversed so that in the above manner this effect can be obtained. To deflect the snow to either side of the roadway I provide the hydraulic cylinder 79 which is attached at 80 to a bracket 81 which is attached at 82 to the casing 21. A piston within the cylinder 79 is attached to a rod 83 and is pivoted at 84 to a cross bar 85.

The cross bar is attached between the two side spout members 86 and the side members 86 include the outwardly bent lower portions 87 which are received within suitable channels 88 at either

side of the casing and above the drum 21 (see Figures 1 and 2). The side members 86 are attached solidly to a further arcuate member 89 which merges with the inwardly inclined portions 87 so that the member 89 also rides within the channels 88, it being understood that any construction can be employed suitable for this purpose. The member 89 includes the opening 90 which is directly over the opening 91 in the drum 21. The opening 91 extends substantially from the points 92 to 93 whereas the opening 90 extends in a more restricted manner from the points 94 to 95. The hydraulic cylinder 79 is suitably connected to the pipe 96 which passes to the vehicle and the cylinder 79 is operated through pressure or suction means to swing the arrangement to one side or the other.

It will be noted that since the sides 76 are attached to the member 89 that when the plunger in the cylinder 79 is operated, the rod 83 will force the entire slidably arranged to one side or the other. For instance, through pressure in the cylinder, the arrangement will be swung to the left thereby bringing the point 94 substantially adjacent to the point 92 and carrying the point 95 further over to the left. This, then, leaves an opening at the left hand side of the drum allowing the snow to be whirled and thrown in this direction and the same operation can be performed for the right hand direction with the fan blades suitably reversed as previously explained. An upper deflecting shield 96 is attached to a shaft 97 which passes through the rear wall 86 and is attached to a suitable small hydraulic motor 98 which is connected through the pipe 99 which passes to the vehicle and which includes one or more small tubes for reversing direction of the hydraulic unit so that the shield 96 can be swung from one side to the other corresponding to the openings effected by the above described arrangement.

Figures 5 and 6 illustrate a modification involving a different reversing arrangement than that heretofore described. In this arrangement, the shaft 100 which is driven from the vehicle similar to the shaft 43 in the foregoing arrangement is attached to a gear 101 which meshes with the larger gear 102 which is rigidly attached to the shaft 27 which shaft is attached to the aforesaid boring hub 28 to which is attached the blades 30. The hollow shaft 103 is attached to the fan structure previously described and slidably engaged with the hollow shaft 103 is the further gear 104 which engages with the lengthened key 105 upon which the gear 104 is free to slide longitudinally but which can not rotate thereupon.

A further gear 106 is attached to the shaft 100 ahead of the gear 101 and is rigidly attached thereto. A gear 107 which extends beyond the gear 106 and which is wider than the same rotates upon a further shaft 108. A further forward gear 109 is keyed to the shaft 100 at 110. The gear 104 includes an indent 111 in which is received the tongue 112 of the rod 113 which extends rearwardly through the casing as shown. As shown in Figure 5 the gears are not engaged, however, when the rod 113 is thrust forwardly, the gear 104 will engage with the gear 109 thereby providing a certain direction of rotation of the fan structure.

If it is desired to reverse the direction, the rod 113 is drawn rearwardly which carries the gear 104 into mesh with the gear 107. This sets up a reverse rotation to the fan structure since the

gear 107 reverses the direction imparted by the shaft 100 and since the gear 107 is constantly in mesh with the gear 101 the fan will be rotated in the opposite direction. The gear 107 is idle until the reversing action is applied.

Through the foregoing structure it will be observed that as the blades 30 cut into the snow that the same is thereby conveyed rearwardly, through the boring action thereof, where it is carried by the small blades 60 toward the center of the machine and into the fan blades which then carry the snow outwardly through the spout arrangement. It will be noted that the lower blades 60 are situated at the most advantageous position for this purpose which is at the lower portions of the plow and it will be noted that they are proportioned in such a manner as to effectively carry the snow directly toward the center of the machine.

It will also be seen that I have provided a snow plow which is properly tilted to provide the most efficient boring action to the units, which includes means for throwing snow to either side of the roadway and that I have provided an arrangement which can be efficiently and readily controlled.

Some changes may be made in the construction and arrangement of the parts of my invention without departing from the real spirit and purpose of my invention, and it is my intention to cover by my claims any modified forms of structure or use of mechanical equivalents, which may be reasonably included within their scope.

I claim as my invention:

1. A snow plow comprising a forward boring and conveying member, having a central shaft, the shaft of such member extending forwardly, said boring member being pitched at a slight angle from the vertical, side cutting members positioned adjacent to said boring member, said side cutting members extending forwardly to the outer cutting limits of said conveying member, a fan mounted rearwardly of said conveying member, a pair of lower conveying members positioned inwardly adjacent said side cutting members and spaced inwardly from said boring member.

2. A snow plow comprising a forward boring and conveying member, having a central shaft, the shaft of such member extending forwardly, said boring member being pitched at a slight angle from the vertical, side cutting member positioned adjacent to said boring member, said side cutting members extending forwardly to the outer cutting limits of said conveying member, a fan mounted rearwardly of said conveying member, a pair of lower conveying members positioned inwardly adjacent said side cutting mem-

bers and spaced inwardly from said boring member, said lower conveying members including a plurality of peripherally and inwardly inclined blades for conveying snow.

5. A snow plow comprising a forward boring and conveying member, having a central shaft, the shaft of such member extending forwardly, said boring member being pitched at a slight angle from the vertical, side cutting members positioned adjacent to said boring member, said side cutting members extending forwardly to the outer cutting limits of said conveying member, a fan mounted rearwardly of said conveying member, a pair of lower conveying members positioned inwardly adjacent said side cutting members and spaced inwardly from said boring member, said lower conveying members including a plurality of peripherally and inwardly inclined blades for conveying snow, said fan including a centrally depressed portion, a casing included in said portion, means for reversing said fan positioned within said casing.
